TION OF DELAWARE.

STARTING MEANS FOR INTERNAL-COMBUSTION ENGINES.

1,253,452.

Specification of Letters Patent. Patented Jan. 15, 1913.

Application filed December 26, 1913. Serial No. 308,900.

To all whom it may concern:

Be it known that I, LEON WYGODSKY, a subject of the Czar of Russia, and a resident of New York, in the county of New York and State of New York, have invented certain new and useful Starting Means for Internal-Combustion Engines, of which the following is a specification.

My invention relates to improvements in means for starting internal combustion engines, and it comprises means for forcing air or other combustion-supporting fluid into the engine cylinder and means for injecting combustible material into such cylinder, together with a simple and highly effective device which holds the piston of the engine stationary in starting position, until a sufficient pressure of the air or other combustion-supporting fluid behind the piston has been reached, and then permits the fly-wheel of the engine to move a few degrees only, as a signal to the engine attendant to inject fuel-fluid into the engine cylinder, and then unlocks the piston altogether. Other features of my invention will be pointed out hereinafter.

The objects of my invention are, to facilitate the starting of internal combustion engines, to make it possible for even very large single cylinder engines or multi-cylinder engines to be started by a single attendant without the necessity of compressing air to high pressure and without storing such air, and with practically the same ease with which a corresponding steam engine would be started, and to make the starting mechanism very simple, also to cause the starting mechanism to indicate visually when a proper pressure has been reached in the engine cylinder.

I will now proceed to describe my invention with reference to the accompanying drawings, and will then point out the novel features in claims.

In the drawings:

Figure 1 shows a side elevation and partial section of an internal combustion engine provided with starting mechanism embodying my invention.

Fig. 2 is a detail side elevation of the locking device of this starting mechanism, a portion of the fly-wheel of the engine being shown in section, and such fly-wheel

being indicated in a slightly different position than the position shown in Fig. 1. 55

Fig. 2^a shows a transverse section through the toggle joint of the locking device of Figs. 1 and 2.

Fig. 3 is a central vertical section of one form of air pump which may be used, the section being taken at right angles to Fig. 1.

Fig. 4 shows a central longitudinal section of a positively lockable check valve which is convenient for use as a part of the starting mechanism. 65

Fig. 5 is a detail section of the oil-pump of the engine, the section being taken through the center of the oil pump and at right angles to Fig. 1, and looking from the rear of Fig. 1. 70

Fig. 6 shows a transverse vertical section through the air-admission and main exhaust valve chambers of the engine, also showing mechanism for operating said valves.

Fig. 7 is a fragmentary longitudinal section of the rear portion of the engine cylinder, the section being taken through the center of the air admission and exhaust valve chambers. 75

Fig. 8 shows, on a scale smaller than Figs. 6 and 7, a detail transverse section of the engine cylinder through the center of the auxiliary exhaust valve, and also shows means for operating said valve. 80

Fig. 9 is a detail side elevation and partial section on a scale larger than Fig. 1, of the mechanism for operating the supplemental exhaust valve, showing means for shifting the cam-operated roller to one side or the other. 85

In the drawings, 1 designates the engine cylinder, 2 (Fig. 6) the piston, 3 the connecting rod, 4 the crank shaft and 5 a fly-wheel on said crank shaft.

The engine cylinder is provided with an extended hollow rear head 6 within which is a combustion chamber 7 (Fig. 7), a suitable air admission valve 8 and a main exhaust valve 9 and supplemental exhaust valve 10 being mounted in this rear head; also an ignition ring 11 and sprayer 12, the ignition ring being of the type covered in my Patent No. 1,076,619, dated October 21, 1913, and the sprayer being of the type covered by my Patent No. 971,954, dated October 4, 1910. A valve operating shaft 13 is driven

from the crank shaft 4 by gears 14 and 15 so constructed as to revolve shaft 13 at half the speed of the crank shaft. Upon this shaft 13 there is a cam 16 arranged to operate a rocker 17 which operates the exhaust valve 9, the same cam being also arranged to operate another rocker 18, connected by a link 19 to a rocker 20 which operates the air admission valve 8. This valve gear is more fully illustrated and described, and claimed, in my companion application for Letters Patent Ser. No. 808,899, now Patent No. 1,166,508, dated Jan. 4, 1916.

While the invention is applicable to internal combustion engines generally, I have illustrated it as applied to an engine of the four-cycle injection type. In Fig. 5, 21 designates the fuel pump and 22 a governor-adjusted cam driven by shaft 13, and arranged to operate the fuel pump; the governor-adjusted cam, and fuel pump, being arranged substantially as shown in my Patents Nos. 971,954 and 1,015,115 and in my companion application filed December 26, 1913, Serial No. 808,899, now Patent 1,166,508, and being arranged to inject oil or other suitable fuel, at or about the end of the compression stroke or beginning of the working stroke, into the sprayer 12 and so into the combustion chamber 7. 23 designates the fuel supply pipe leading from the pump 21 to the sprayer 12.

As previously stated, means are provided for supplying air or other combustion-supporting fluid, under pressure, to the engine cylinder, for starting the engine. In Figs. 1 and 3, 24 designates a reciprocating pump cylinder and 25 a stationary pump piston, of an air pump for supplying air or other combustion-supporting fluid to the engine cylinder and also to a suitable torch for heating preliminarily the ignition ring 11. Without limiting myself to the use of any particular type of pump, I will state that the particular form of pump shown is convenient and suitable for the purpose. 26 designates a bell-crank foot lever for moving the compression cylinder 24 downward, 27 a spring for moving such cylinder upward, 28 an air admission valve, 29 a spring actuated discharge valve in the head of the stationary piston 25, such valve arranged to discharge the compressed air into the interior reservoir 25^a of the hollow stationary piston 25, and 30 a link to which the lower arm of lever 26 is pivoted; 31 a pipe for conveying air from this reservoir 25^a to the torch 32 (see also Fig. 7); 32^a a pipe for conveying combustible (oil or gas) to said torch, and 33 a pipe for conveying compressed air from the pump to the combustion chamber 7 and so to the engine cylinder. I preferably provide a spring loaded valve 33^a (Fig. 3) preventing discharge of air from reservoir 25^a into pipe 33 until after a certain pressure, sufficient

for the operation of the torch 32, has been reached in reservoir 25^a; and I preferably provide a positively lockable check valve illustrated in Fig. 4 and hereinafter described, for preventing back-flow of gas from the engine cylinder and combustion chamber into pipe 33, when an explosion in the engine cylinder occurs.

The connection between the foot-lever 26 and the reciprocating cylinder 24 are such that during the early portion of the compression stroke, when the resistance to motion of the cylinder is small the leverage is small, while near the end of the compression stroke, when the resistance to motion of the piston is great, the leverage is great. Thereby a nearly uniform resistance to motion of the foot-lever is obtained; *i. e.*, the load on the foot lever is nearly uniform.

In starting mechanism such as herein described, it is important that the piston be held stationary until sufficient air pressure has been accumulated, behind the piston, to insure combustion of a charge of fuel injected past the ignition device 11 into the combustion chamber 7; and it is also important to provide means for indicating visually to the engine attendant, when such pressure has been reached behind the engine piston, so that he may know when to introduce a charge of fuel. A pressure gage on the pipe 33, or on the engine cylinder, is not an altogether satisfactory means for indicating when the desired pressure has been reached, partly because a pressure gage if connected to the pipe 33, will be affected by the necessarily intermittent discharge of the pump 24, while a pressure gage directly connected to the engine cylinder may be affected by the heat in that cylinder; and partly because engines will at times require greater air pressure for starting than at other times.

I have found that the best means for indicating when the desired pressure has been reached in the engine cylinder is a locking device which holds the piston stationary until the desired pressure has been reached, then permits a very slight motion of the piston (and, therefore, of the fly wheel) as an indication that the desired pressure has been reached, and then holds the fly-wheel and piston stationary until, following the injection of fuel into the engine cylinder, and combustion of such fuel, the pressure behind the piston increases very greatly; thereby causing the piston to move forward and the fly-wheel to revolve; whereupon this positive locking mechanism should then go completely out of engagement with the fly-wheel. A very simple and positively operating locking device such as referred to is illustrated in Figs. 1 and 2, comprising a dog 34 adapted to engage a recess 35 in the fly-wheel; a lever 36 pivoted to some stationary

portion of the engine, and provided with a spring 37 tending to press it forward, and toggle links 38 and 39 connecting the lever 36 and the dog 34. The pressure exerted by spring 37 upon lever 36 is readily adjustable by means of a nut 40 on the spring-rod 41. Nuts 40^a serve as a stop for lever 36 against spring 37, and serve to adjust the action of dog 34.

10 When the dog 34 first engages the end of recess 35 of the fly-wheel the very end 42 of such pawl engages the end of such recess, as indicated in Fig. 1. When a sufficient pressure has been pumped up, behind the 15 engine piston 2, to move the piston forward, the point of engagement of the fly-wheel with the dog 34 shifts from the very point of the dog to a point 43 somewhat farther back, as illustrated in Fig. 2; and 20 owing to the shorter radius of point 43 than point 42, the pressure which was sufficient to start the piston, with the dog 34 in the position shown in Fig. 1, is not sufficient to 25 continue motion of the piston with said dog in the position shown in Fig. 2. Consequently, the motion of the fly-wheel is through a very few degrees only, but such motion is sufficient to be noticed by the 30 engine attendant, who thereby understands that sufficient pressure has been reached in the engine cylinder for the starting of the engine. The ignition ring 11 having previously been heated to a temperature sufficient to 35 ignite an entering charge of fuel (such preheating having been effected by means of the torch 32) the engine attendant thereupon operates the fuel pump 21 by means of the hand lever 44 so injecting a charge of fuel through the sprayer 12 and past the 40 ignition ring 11 into the combustion chamber 7, and since this combustion chamber is already filled with air under considerable pressure, the fuel so injected will immediately ignite and thereby greatly increase the 45 pressure within the combustion chamber 7 and engine cylinder 1, thereby starting the engine piston 2 forward against the resistance offered by the dog 34, and forcing the lever 36 back against the pressure of spring 50 37 until the toggle 38-39 reverses, such reverse position being indicated in dotted lines in Fig. 1. In the reverse position of the toggle 38-39 the dog 34 is completely out of engagement with the fly wheel, and will 55 remain out of such engagement during the continued operation of the engine. As a convenient means for resetting the dog 34, after the engine has stopped, I make the connecting pin 45 of the toggle 38-39 removable. When the toggle is in the reverse position, indicated in dotted lines in Fig. 1, the mere removal of this pin 45 makes it possible to swing the parts of the toggle to the position shown in full lines in Fig. 1 60 65 the fly wheel 5 having first been moved

until its recess 35 is opposite the dog 34) and then, upon reinsertion of the pin 45, the toggle locking mechanism is connected up ready for use; and this resetting of the toggle mechanism is accomplished, it will be 70 seen, without movement of the lever 36 against the pressure of spring 37. Of course, the toggle mechanism might be reset by forcing the lever 36 backward; but this would involve considerable effort, particularly in the case of a large engine; whereas by the mere removal of the pin 45 it is possible to reset the toggle without forcing back the lever 36, and therefore it is substantially as easy to reset the toggle in a very 75 large engine, as in a small engine.

Upon valve-cam shaft 13 there are two cams 61 and 61^a adapted to engage an anti-friction roller 62 (Figs. 1 and 8) on a follower lever 47 connected to the stem of the 80 supplemental exhaust valve 10. A spring 63 tends to hold valve 10 closed. Cam 61 is arranged to engage roller 62 to open valve 10 slightly in advance of the opening of the main exhaust valve 9, so releasing pressure 85 in the engine cylinder just before the main exhaust valve opens, and thereby making it easier to open such main exhaust valve. In the normal position of roller 62, shown in Fig. 1, cam 61^a does not engage roller 62 at 90 all; but as shown in Fig. 9 this roller 62 may be moved laterally to a position in which it will be engaged both by cam 61 and by cam 61^a. And cam 61^a is so located and proportioned as to open valve 10 and 95 hold it open during a portion of the compression stroke of the engine piston, thereby reducing the compression pressure, and so facilitating the starting of the engine. To hold the roller 62 in the one position or the 100 other to which it may be adjusted, two holes 62^a and 62^b are provided in the axle about which this roller rotates, and a pin 62^c is provided which may be thrust through either of these holes, thereby holding the 105 roller 62 in one lateral position or the other.

The starting of the engine by the means hereinbefore described, is accomplished as follows:

If the engine fly wheel has not been 115 stopped in the starting position such fly wheel is turned over by hand, until just below starting position, and such turning over is facilitated by opening the auxiliary exhaust valve 10, which then operates as a release valve. For so opening the auxiliary exhaust valve I provide a hand-lever 46 (Figs. 6 and 8) which, when raised, depresses the operating lever 47 of this release valve 10, so opening said valve. When the 120 fly wheel has been moved around to just below starting position, the release valve 10 is closed, the pin 45 removed from the toggle and the dog 34 reset in the recess 35 of the fly wheel and the pin 45 again inserted. 125 130

The roller 62 of the valve mechanism of the supplemental exhaust valve 10, is then shifted to the position shown in Fig. 9, in which it will be engaged by the cam 61^a.
 5 The pump lever 26 is then operated to supply air under pressure for the operation of the torch 32, the operation of the pump compressing air into the reservoir 25^a of the pump. At first air is discharged from 10 this reservoir through pipe 31 only to the torch; but very soon a sufficient pressure is reached within this reservoir to open the valve 33^a, whereupon the compressed air in excess of that required for the torch passes 15 through pipe 33 into the combustion chamber and engine cylinder. The escape of such excess compressed air through pipe 33 serves to maintain within the reservoir 25^a a substantially uniform pressure for the operation 20 of the torch. The air passing over into the combustion chamber and engine cylinder will soon reach a pressure sufficient to move the piston forward slightly, bringing the bottom of the recess 35 of the fly wheel 25 into engagement with the end 42 of the locking dog 34, and so bringing the piston accurately to starting position. The fly wheel and piston will remain in this position until air has been compressed to a suitable higher 30 pressure within the combustion chamber and engine cylinder to overcome the pressure of spring 37 exerted through the toggle links 38-39 and dog 34, and to move the fly wheel from the position shown in Fig. 1 to the 35 position shown in Fig. 2.
 By the flame of the torch 32 the ignition ring is very quickly heated to a temperature sufficient to ignite an incoming charge of fuel. In practice, I have found that the ignition 40 ring is so heated by the torch within from thirty to sixty seconds, and preferably I make the air pump of such capacity that such pump, operated at a convenient rate, will have compressed air within the engine 45 cylinder to an extent sufficient to move the fly wheel from the position shown in Fig. 1 to the position shown in Fig. 2, by the time the torch has heated the ignition ring sufficiently to ignite an incoming charge of fuel.
 50 Exact accuracy in this respect is not required, as it does no harm to heat the ignition ring somewhat beyond the minimum temperature at which it will ignite an incoming charge; but reasonable accuracy in 55 this respect is readily attainable, for different engine attendants will operate a foot pump such as shown at nearly the same rate, being the natural rate of movement of the foot, which does not differ greatly with different people, and therefore it is easy to so coordinate the capacity of the air pump, the heating capacity of the torch 32 and the rate of heating of the ignition device 11, that by the time the ignition device 11 is sufficiently 60 hot to ignite an incoming charge of fuel, or

very shortly thereafter, sufficient pressure will have been reached in the combustion chamber and engine cylinder to move the fly wheel from the position shown in Fig. 1 to the position shown in Fig. 2, in which latter 70 position the fly wheel will be arrested owing to the shorter radius of the point 43 at which the fly wheel now engages the dog 34, and, therefore, the still greater pressure required in the engine cylinder to move the fly wheel 75 beyond this second point of arrest. The movement of the fly wheel from the position shown in Fig. 1 to the position shown in Fig. 2, though slight, is sufficient to attract the attention of the engine attendant, 80 and the ignition ring 11 having by this time become heated sufficiently for ignition of an entering charge, the engine attendant immediately operates the fuel pump 21, one or more times, as may be thought 85 necessary, by means of the hand lever 44; whereby a charge of oil is injected through the sprayer 12 and past the ignition ring 11 into the combustion chamber 7, and such charge of the fuel immediately ignites in the 90 compressed air already within that combustion chamber, and the resulting increase in pressure behind the engine piston 2 moves the piston and fly wheel forward against the resistance of the dog 34, reversing the toggle 95 38-39, and so automatically disengaging the dog 34 from the fly wheel.

The impetus so imparted to the engine piston 2 and fly wheel 3 by the introduction and ignition of the first charge of oil, will in 100 many cases be sufficient to carry the engine throughout one expansion, exhaust, air admission, and compression cycle; i. e., two revolutions of the fly wheel. The next injection of oil will take place automatically 105 by the automatic operation of the fuel pump 21 by cam 22, which new charge will be ignited by the ignition ring 11, and thereupon the engine will continue in its cycle, and it is no longer necessary to operate the air 110 pump 24 or the torch 32.

These operations required for the starting of the engine are very easily and simply and quickly performed, and in practice the engine starts as easily and about as quickly 115 as if it were a steam engine.

The pressure of the spring 37 may be regulated, by means of the nut 40, so that any particular desired air pressure in the cylinder will be reached before the fly wheel 120 moves from the position shown in Fig. 1 to the position shown in Fig. 2. By means of the nuts 40^a the position of the dog 34 may be changed so as to vary the position of the fly wheel at which engagement of such fly 125 wheel with the end 42 of the dog 34 occurs. After the engine is well started, the roller 62^a is shifted back to normal position so that the half compression cam 61^a no longer engages it and the valve 10 is no longer opened 130

during the compression stroke; full compression being then reached in the engine cylinder.

While it is convenient to employ a half compression cam 61^a and means operated thereby for decreasing compression pressure during the starting of the engine, it will of course be understood that such half compression cam and means operated by it is not necessary for the starting of the engine. In case no half compression cam is provided sufficient pressure must be pumped up in the combustion chamber during the preliminary starting operations, and sufficient fuel must be injected into the combustion chamber for the first explosion, to supply sufficient energy to carry the piston nearly through, and preferably completely through, the compression stroke, so that the engine will function automatically after such compression stroke is passed. Should the engine attendant see that the piston will not completely pass through the compression stroke, he may operate the oil pump just before, or just as, the piston comes to rest, so starting the piston forward again and starting the fly wheel in backward rotation; and during this backward rotation the engine exhausts through what is normally the air admission valve, 8, and draws in air through what is normally the exhaust valve 9. Near the end of the compression stroke in reverse rotation (the stroke that would be the expansion or working stroke in normal operation) the engine attendant will again operate the fuel pump, producing a stronger explosion in the engine cylinder, and so starting the piston forward and starting the fly wheel in forward rotation; and the impetus thus imparted to the fly wheel will be, in general, sufficient to cause the engine to function automatically thereafter; otherwise the operations of starting the engine in reverse rotation and starting it again in forward rotation, may be repeated.

It will, of course, be understood that the compressed air for starting and for operation of the torch 32, may be supplied from any other convenient source instead of the foot pump 24; and, in a broad sense, this foot pump constitutes a diagrammatic representation of any suitable source of compressed air or other combustion-supporting fluid.

To prevent the gases of the engine cylinder from passing back through pipe 33, into the reservoir 30, I preferably provide a spring actuated check valve 48 (Fig. 4) which the air forced through pipe 33 opens against the pressure of the valve spring 49; such valve being mounted within a bushing 50 suitably secured in the side wall of the combustion chamber 7. As in injection engines the compression pressure is preferably moderately high (say from two hundred

and fifty to three hundred pounds per square inch) it is desirable that this check valve be closed positively once the engine is in full operation; and therefore for this purpose I provide a hand wheel 51 having a screw thread connection with the end of the bushing 50 and also having a shoulder 52 engaging a collar 53 on the stem of the valve 48. It will be apparent that by rotating this hand wheel 51 the valve 48 may be drawn up tightly against its seat, or may be released so as to be opened, against the action of its spring 49, by air under pressure forced in through pipe 33.

The shoulder 51^a of hand wheel 51 is arranged to form a tight joint with the shoulder 51^b of bushing 50 when hand wheel 51 has been turned to release the valve 48 to permit it to open. This prevents escape of air and gases through the screw-threaded joint between the hand wheel 51 and the bushing 50.

I do not in this application claim the novel engine frame herein illustrated but not specifically described, as the same is claimed in my companion application filed December 26, 1913, Serial No. 808,898, now Patent No. 1,114,217, dated October 20, 1914. I do not in this application claim the auxiliary or supplemental exhaust valve 10, and the means for operating it, as the same is claimed in my companion application docket filed December 26, 1913, Serial No. 808,901, now Patent No. 1,156,123, dated October 12, 1915, itself a division of my application Sr. No. 755,950. This supplemental exhaust valve constitutes a very convenient means for stopping the engine in the starting position. In stopping an engine of this type the common practice is to cut off the supply of fuel, after which the fly wheel continues to rotate for some time, due to the inertia it has acquired, until finally the inertia of the fly wheel is unable to overcome the compression pressure near the end of the compression stroke of the piston. The fly wheel then comes to rest, but immediately starts in backward rotation, due to the expansion of the air compressed within the cylinder, and rotates backward until the piston again compresses air in the cylinder. The inertia of the fly wheel being, of course, insufficient to enable the piston to complete this backward compression stroke, said piston comes to rest near the end of such stroke; and if, just as the piston so comes to rest, the auxiliary valve 10 is opened, by raising the lever 46, so releasing the pressure within the engine cylinder, the piston and fly wheel remain in such position with the parts of the engine in about the proper position for starting. The hand lever 46 is provided with a cam portion 55 which, when the hand lever is raised, depresses a push rod 56 against the action of a spring 57, this push

rod engaging a pin 58 projecting from the lever 47 engaging the stem of the auxiliary exhaust valve 10.

The supplemental exhaust valve 10 and the two cams 61 and 61^a, the one for opening the valve 10 prior to the opening of the main exhaust valve, and the other for opening the valve 10 during a portion of the compression stroke, are claimed in my companion application, Serial No. 808,901, now Patent No. 1,156,123, dated October 12, 1915, and therefore are not claimed herein. The valve 10 has many functions besides that of facilitating the turning over of the engine during the starting thereof.

While I have illustrated and described the engine as provided with a foot operated air pump for compressing air in the engine cylinder, it will be obvious that, in the case 20 of small engines at least, it is practicable to dispense with such separate air pump and to compress air in the cylinder by turning the fly wheel, manually or otherwise, and thus compressing air within the engine cylinder by the action of the engine piston 2, the piston being stopped at the starting position and held there, until the injection of the fuel by the piston-holding means of which the dog 34 is a part. In the case of 25 a small engine particularly, it is entirely practicable to throw the piston holding means from the disengaged position shown in dotted lines in Fig. 1, to the engaging position shown in full lines in Fig. 1, manually 30 or otherwise, and without removing the toggle pin 45; and when the air for starting the engine is to be compressed within the engine cylinder by motion of the engine piston 2, this piston holding means will 35 commonly be thrown into engaging position 40 without removal of the toggle pin 45.

What I claim is:—

1. In an internal combustion engine, the combination with an engine cylinder and piston, means for introducing air into said cylinder and means for introducing fuel into said cylinder, at the will of the operator, said cylinder provided with ignition means arranged to ignite such fuel at entrance, of means for holding said piston stationary until the admission and ignition of the fuel, such piston-holding means arranged to release the piston automatically after a predetermined pressure in the cylinder has been reached.

2. In an internal combustion engine, the combination with an engine cylinder and piston, means for compressing air in said cylinder and means for supplying fuel to said cylinder, after the compression of the air therein, said cylinder provided with ignition means adapted to ignite a charge within said cylinder irrespective of the position of the engine piston, of means for holding 65 said piston stationary until a predetermined

pressure has been reached in the engine cylinder, such piston-holding means arranged to release the piston automatically after a predetermined pressure in the cylinder has been reached.

3. In an internal combustion engine, the combination with an engine cylinder and piston, means for compressing air in said cylinder at the will of the operator, and means for injecting fuel into said cylinder after the compression of the air therein, said cylinder provided with ignition means adapted to ignite such fuel immediately upon the injection thereof into such cylinder, of means for holding said piston stationary until the fuel so injected is ignited, such piston-holding means arranged to release the piston automatically after a predetermined pressure in the cylinder has been reached.

4. In an internal combustion engine, the combination with an engine cylinder and piston, means for introducing air into said cylinder and means, including a fuel pump operable at the will of the operator, for injecting fuel into said cylinder, said cylinder provided with ignition means adapted to ignite fuel so injected upon entrance to the engine cylinder, of means for holding said piston stationary until the injection and ignition of such fuel, such piston-holding means arranged to release the piston automatically after a predetermined pressure in the cylinder has been reached.

5. In an internal combustion engine, the combination with an engine cylinder and piston, crank shaft, and connecting rod, of a locking member adapted to engage a portion of the engine movable with said piston and thereby to hold the piston stationary 105 against pressure against said piston, a toggle mechanism arranged in one position of the toggle to hold said locking member in engaging position and in a reversed position of the toggle to hold said locking member 110 out of engaging position, and means resisting motion of the toggle from engaging to disengaging position of the locking member.

6. In an internal combustion engine, the combination with an engine cylinder and piston, crank shaft and connecting rod, of a locking member adapted to engage a portion of the engine movable with said piston and thereby to hold the piston stationary against pressure against said piston, a toggle 115 mechanism arranged in one position of the toggle to hold said locking member in engaging position and in a reversed position of the toggle to hold said locking member 120 out of engaging position, and spring means 125 resisting motion of the toggle from engaging to disengaging position of the locking member.

7. In an internal combustion engine, the combination with an engine cylinder and

5 piston, crank shaft, connecting rod, and a fly wheel on said crank shaft, of a locking dog adapted to engage said fly wheel in one position thereof, and thereby to hold the 10 piston stationary against pressure against said piston, a toggle mechanism operatively connected with said dog, and adapted in one position to hold the dog in engagement with the said fly wheel and in a reversed position of the toggle to hold said dog out of engagement with said fly wheel, and means resisting motion of the toggle from the one position to the other.

8. In an internal combustion engine, the 15 combination with an engine cylinder and piston, crank shaft, connecting rod, and a fly wheel upon said crank shaft, of a pivoted locking dog arranged to engage the fly wheel in one position thereof and hold such 20 fly wheel stationary against motion of the piston, a spring actuated lever, and a toggle intermediate said lever and dog and operatively connected to both, said toggle arranged in one position to hold the dog in a 25 engagement with said fly wheel, and in a reversed position to hold the dog out of engagement with said fly wheel.

9. In an internal combustion engine, the 30 combination with an engine cylinder and piston and mechanism operated thereby, of piston arresting mechanism comprising means adapted to engage and arrest a movable portion of said piston-operated mechanism, said piston-arresting mechanism arranged to hold the piston until a predetermined pressure is exceeded and then to permit slight motion of the piston and again arrest it and hold it in such second position until a further predetermined pressure has 40 been exceeded.

10. In an internal combustion engine, the combination with an engine cylinder and piston and mechanism operated thereby, of piston arresting mechanism comprising a pivoted dog arranged to engage a portion of said piston-operated mechanism and hold the same, said piston-arresting mechanism comprising pressure-exerting means tending to hold the dog in such engaging position 45 until a predetermined pressure against the piston is exceeded, the member of the piston-operated mechanism so engaged arranged, when such predetermined pressure is exceeded, and the piston has moved, to again 50 engage said dog at a point of shorter radius than that at which the initial engagement of the dog occurred, whereby the piston is again held until a further predetermined pressure is exceeded.

60 11. In an internal combustion engine, the combination with an engine cylinder and piston, mechanism operated by the piston, and means for introducing fuel into said

cylinder, at the will of the operator, said cylinder provided with ignition means arranged to ignite such fuel at entrance, and means for holding such piston stationary until admission and ignition of the fuel, such piston-holding means comprising a 65 detent member, adapted to engage a movable member of the piston-operated mechanism, such detent member having two positions of engagement with such movable member and arranged to shift from the first position of engagement to the second position of engagement when a predetermined pressure against the piston is exceeded, and to release such member of the piston-operated mechanism altogether when a further predetermined pressure against the piston is exerted. 70 75

12. In an internal combustion engine, the combination with an engine cylinder and piston, means for introducing fuel into said cylinder, at the will of the operator, an ignition device adapted to be heated and 85 by its heat to ignite the fuel so introduced, and means for heating said ignition device, of means for compressing fluid under pressure into said cylinder and means for holding said piston stationary until a predetermined pressure of such fluid has been reached in such cylinder, the compressing means being of such capacity with reference to the rate at which such ignition device is heated by the heating means thereof, that 90 said ignition device will be at a temperature capable of causing ignition of the entering fuel, by the time pressure sufficient to start the piston has been reached in the engine cylinder. 100

13. In an internal combustion engine, the combination with an engine cylinder and piston, means for supplying fuel to said cylinder and an ignition device for the fuel so introduced and a burner for heating such 105 ignition device, of a compressor arranged to deliver combustion-supporting fluid to said burner and also to the engine cylinder and a loaded discharge valve through which the combustion supporting fluid passes on its 110 way to the cylinder, said valve loaded to open only after sufficient pressure for the operation of the burner has been reached in rear of such discharge valve; whereby the discharge of fluid through such discharge 115 valve serves to prevent a higher pressure being reached in rear of such discharge valve than is required for operation of the burner.

In testimony whereof I have signed this 120 specification in the presence of two subscribing witnesses.

LEON WYGODSKY.
